ILLINOIS.

CARTON FILLING AND FORMING MACHINE.

1,179,448.

Specification of Letters Patent. Patented Apr. 18, 1916.

Application filed May 13, 1914. Serial No. 838,234.

To all whom it may concern:

Be it known that we, MICHAEL J. MILMOE and FRANK B. REDINGTON, citizens of the United States, residing at Chicago, in the 5 county of Cook and State of Illinois, have invented certain new and useful Improvements in Carton Filling and Forming Machines, of which the following is a specification.

10 Our invention relates to carton filling and forming machines and has for its primary object the provision of an improved machine of that class which shall have improved means for positioning articles to be contained upon a carton blank and forming the 15 blank into a carton about the articles.

With the above and other objects in view, this invention consists substantially in the combination, arrangement, and construction 20 of parts all as hereinafter described, shown in the accompanying drawings which form a part of this specification and illustrate the preferred embodiment of our invention, and more particularly set forth in the subjoined 25 claims.

In the drawings,—Figure 1 is a front elevation of our invention, with parts broken away; Fig. 2 is a rear elevation of the same, with parts broken away; Fig. 3 is a section 30 taken approximately on line 3—3 of Fig. 1; Fig. 4 is an enlarged detail view of portions of Fig. 1; Fig. 5 is a section taken approximately on line 5—5 of Fig. 4; Fig. 6 is a section taken approximately on line 6—6 35 of Fig. 5; Fig. 7 is a view of portions of Fig. 4 showing a different position of the parts; Fig. 8 is a side elevation of the mechanism for feeding carton blanks, parts being broken away and parts being sectioned; Fig. 9 is a front elevation in detail of a 40 portion of the carton blank-feeding mechanism shown in Fig. 8; Fig. 10 is a side elevation of one of the parts shown in front elevation in Fig. 9 and broken away in Fig. 45; Fig. 11 is a section taken on the line 11—11 of Fig. 9, with the carton blanks omitted for the sake of clearness; Fig. 12 is a plan view of a carton blank; Fig. 13 is a view in perspective of the carton filled and 50 formed by this machine; Fig. 14 is an enlarged partial section taken approximately on line 14—14 of Fig. 4 and illustrating in dotted lines an adjusted position of parts; Fig. 15 is an enlarged detail of part of a 55 crayon-feeding device shown in Fig. 1.

Briefly stated, this machine employs carton blanks such, for instance, as illustrated in Fig. 12, delivers them one at a time from a carton blank container, shown in Figs. 1 and 8, to a device illustrated in section in Fig. 14 which turns up two side flaps of the carton, and thence to parts which hold it while an adhesive is applied to its rearward flap and a plurality of crayons are deposited upon it, this holding mechanism being considered hereafter in the description as the center of the whole machine. The crayon-feeding and positioning devices are best illustrated in Figs. 5 and 6. After the crayons are positioned upon the carton blank, the 60 blank is folded about them and carried through approximately a quarter of a circle to the receiving end of a filled carton magazine illustrated in Figs. 1 and 7, into which the carton is pushed and wherein the glued 65 rearward flap is pressed against the forward flap until adhesion between them is complete. 70

Throughout the drawings, reference numeral 20 indicates the framework for the 75 various parts of the machine. A pulley 21 (see Fig. 3), provided with suitable clutch mechanism, rotates a main shaft 22 from which power is supplied to all parts of the machine. Preferably the clutch device is 80 operable from either of two handles 23 (see Figs. 1 and 3).

The crayons which this machine is adapted to infold are placed in a magazine, generally indicated by A (see Figs. 1, 2 and 3), 85 comprising in the present instance nine chambers 24 for the accommodation of nine different colors of crayons. The crayons employed are of equal length and lie horizontally in the chambers 24, preferably with 90 their pointed ends facing forward. At the bottom each chamber 24 is contracted into a throat 25 of an internal diameter approximating the diameter of the crayons, and the throats converge as they pass downwardly 95 from the chambers, terminating in a common plane rearwardly of the center of the machine and slightly thereabove, as shown most clearly in Fig. 5. The lower or discharge ends of the throats 25 are shown at 100 26 in Fig. 5. At the meeting points of the chambers 24 and throats 25 are positioned rollers 27 (see Figs. 1 and 15). These rollers are mounted for rotation about horizontal axes and their function is primarily 105 110

to agitate the mass of crayons in each chamber to prevent bridging of the crayons and to insure a steady flow of the crayons through the throats 25. For the purpose of agitating the crayons, each of the rollers 27 is notched as at 28 in a manner to permit its catching, carrying and releasing one or more of the crayons at each passage of the notch across the bottom of the chamber. If desired the rollers may be made octagonal, as illustrated in the drawings. The rollers 27 are operated by power received from the main shaft, preferably by means of chains and sprockets as shown in Fig. 2. By reason of the opposite direction of slant of the chambers 23 and throats 25 on opposite sides of the vertical median line of the magazine A, the rollers are rotated in opposite directions on opposite sides of this line, this change in direction being accomplished in any suitable manner, preferably by means of the chain 29 and a sprocket 30 fixed upon the rear end of each roller 27, the chain 29 engaging the upper side of the sprockets on one side of the median line and the lower side of the sprockets on the opposite side of the median line. The rollers on opposite sides of the median line of the magazine rotate in the opposite directions indicated by the arrows 31 and 32. The notches 28 of the rollers engage the sides of crayons positioned at the bottom of the chamber and carry the engaged crayons toward the throat of the chamber, the engaged crayons agitating the adjacent crayons in the magazine as they are carried forward by the roller toward the throat. The action of the roller is such that each of the throats 25 is kept filled with crayons, which descend through the throats to the discharge ends 26 thereof.

At 33, in Figs. 1, 2, 4 and 8, is indicated generally a container for carton blanks. The carton blanks are indicated generally by B (see Fig. 12). These blanks B are so cut as to form, when folded, the carton illustrated in Fig. 13, and they are likewise scored as indicated by dotted lines in Fig. 12. The blanks B comprise each a bottom 34, a forward end piece 35, a rearward end piece 36, side pieces 37 and 38, side flaps 39 and 40, a top 41 and a rear end flap 42. The bottom B is outlined by scored lines 43, 44, 45 and 46. The forward and rearward ends of the top are outlined by scored lines 47 and 48, and scored lines 50 and 51 are provided between the side flaps 39 and 40 and their respective side pieces 37 and 38. The bending of the various parts of the carton blank B upon the scored lines forms the carton C.

A stack of the blanks B, horizontally positioned, is placed in the container 33 and preferably a weight 52 is provided upon a plate 53 which rests on the top of the stack 65 of blanks. The bottom of the container is

open and the stack of blanks rest at their rear ends upon a polished bar 54 and at their forward ends upon a polished steel roller 55, provided in its periphery with a segment 56 of rubber. The roller 55 rotates about a shaft 57, which receives its power from the main shaft 22 (see Fig. 2). The roller 55, rotating on a horizontal axis, feeds the lowermost blanks B forward from the bottom of the container 33 to a pair of feeding rolls 58 and 58^a (see Fig. 8), by means of contact between the rubber segment 56 and the lowermost blank of the stack. At its bottom the inner surface of the forward web 33^a of the container 33 is beveled, as at 59, and the forward web terminates at a point somewhat below the normal lower level of the stack of blanks, for the purpose of partially separating the forward edges of the blanks during the process of discharge from the container. As the rubber segment 56 strikes the lowermost blank of the stack, it urges that blank forward, and because of a slight friction between the blanks it urges forward also a number of the blanks just above the bottom one, as shown by Fig. 8. By means of the long beveled surface 59, the forward edges of the cartons are somewhat separated from each other, as shown in Figs. 8 and 9. A guide member 60 is provided at the outer edge of the forward web 33^a of the container and over it the side piece 38 passes. For the purpose of preventing the discharge of more than one blank at a time a detent 61 (see Figs. 8, 9 and 11) is provided, preferably fixed to the forward web 33^a between the guide 60 and the web, this detent contacting with the forward edge of the end piece 38 of the blank just above the lowermost one, to prevent forward travel of all but the lowermost one, the spacing between the bottom of the detent 61 and the top of the guide 60 being sufficient to allow the passage of one blank but not sufficient to allow the passage of two. The lower extremity of the forward web 33^a of the container terminates approximately level with the upper surface of the guide 60, by means of which construction the forward end of the side piece 38 is positively positioned upon and in contact with the upper surface of the guide 60 as each carton passes out. As shown in Figs. 10 and 11, the guide 60 though supported by the forward web 33^a, is offset backwardly to place it in proper position for the support of the side piece 38. The rotation of the roller 55 when the segment 56 strikes the lowermost blank forces the forward edge of the lowermost blank to the bottom of the bevel 59, in which position the forward end of the side piece 38 lies in contact with the upper surface of the guide 60, the segment 56 being of sufficient length to feed the lowermost carton blank forward into the dotted position shown in Fig. 8, 130

and between the feeding rolls 58 and 58^a. Contact between the forward end of the side piece 38 of the next-to-the-bottom blank and the detent 61 prevents the feeding forward of the next-to-the-bottom blank, and obviously those above the next-to-the-bottom blank are retarded should friction carry them forward against the detent. That part of the periphery of the roller 55 not covered with rubber being of polished steel has no feeding effect upon the blanks in the container 33, by reason of which construction one blank is fed forward to the feeding rolls 58 and 58^a for each rotation of the roller 55, the feeding function being performed only when the rubber segment 56 contacts with the lowermost blank. Upon the outer end of the roller 55 is formed a cam track 62, provided with a raised cam portion 63.

20 A tapper 64, supported by means of a piece of spring metal 65, secured to the body of the container extends vertically of the stack of blanks B in the container 33 and is pressed against the sides of all the blanks by means of the support 65. At its lower end the tapper 64 is formed into a cam finger 66 which rides upon the cam track 62. At each passage of the elevation 63, the tapper 64 is removed a short distance from the stack of blanks and subsequently brought back forcibly against it by means of the spring support 65, for the purpose of maintaining the blanks in proper superposed position within the container. The feeding rolls 58 and 58^a feed the carton released from the container 33 forwardly over a polished steel guide 67 to a similar pair of feeding rolls 68 and 68^a, which in turn pass it forward to a flap-turning device illustrated in detail in Fig. 14. In this device the carton B is bent upon the scored lines 50 and 51, as illustrated in dotted lines in Fig. 14. A platen 69 (see Figs. 4 and 14), suitably supported by the frame 20, forms the foundation of the flap-turning device detailed in Fig. 14. Upon the sides of the platen are pivoted, as at 70 and 71, folding fingers 72 and 73 which are adapted to oscillate about their pivots from the full line positions to the dotted line positions shown in Fig. 14. In this oscillation the fingers 72 and 73 turn upwardly and fold inwardly the side flaps 39 and 40. To insure the folding of the flaps upon the scored lines 50 and 51, a forming plate 74 is positioned above the platen 69 and spaced therefrom a distance sufficient to permit the passage of the carton blank B. The forming plate 74 is supported in any suitable manner, preferably by means of lugs 75 at its rear end. Means for oscillating the fingers 72 and 73 are provided in a pair of links 76 and 77 pivoted at their upper ends to the fingers and at their lower ends upon a pivot rod 78, which by means of an arm 79 is

oscillated about a pivot post 80. The arm 79 is actuated in any suitable manner by power received from the main shaft 22. As the carton blank B passes through the flap-folding device of Fig. 14, the side flaps 39 and 40 protrude laterally beyond the forming edges of the plate 74 and are folded upwardly, as illustrated in dotted lines, the angle formed between the folded side flaps and the remainder of the blank being preferably more acute than that desired in the finished carton, for the reason that the material of which the blank is formed will cause the flaps to spring back from the acutely angled position shown in Fig. 14 to the right angled position desired in the finished carton C. The oscillation of the pivot bar 78 from the full line position to the dotted line position of Fig. 14 folds the side flaps 39 and 40, and reciprocation of the pivot bar returns the fingers 72 and 73 to the full line position, wherein they lie below the level of the blank-receiving surface of the platen 69, in which latter position the fingers do not obstruct the feed of the next blank to the flap-forming device.

The forming plate 74 is extended forwardly, as at 81, and spaced directly below the forward extension 81 is a feed roll 82 having its feeding surface on a level with the blank-receiving surface of the platen 69. The blank B, as it leaves the flap-folding device, is fed forward between the extension 81 and the roll 82, between two retaining arms 83 and 84 and upon two supporting arms 85 and 86 (see Figs. 5 and 7). Inwardly extending shoulders 87 and 88 are formed upon the retaining arms 83 and 84, respectively, and a third retaining arm 89 directly above the arm 84 is provided inwardly and upwardly beveled on its inner surface to form a support upon which is secured a stop 90, which depends from the upper inner edge of the arm 89. The lower end of the stop 90 is spaced above the upper blank-receiving surface of the supporting arm 86 a distance slightly greater than the thickness of the blank. A supporting plate 91, secured in any suitable manner to the frame 20, extends forwardly from a position beneath the bottom of the crayon magazine A and its forward end lies flush with the upper edge of the inner surface of the retaining arm 83, from which point it is beveled upwardly and inwardly toward the retaining arm 84 to form a support for the folded flap 39. The folded flap 40 is supported from bending outwardly too far by the retaining arm 89 and lies in a recess formed by the stop 90 and the arms 84 and 89.

Notches 92, shown in Figs. 4 and 7, are provided in the arms 83 and 84, registering opposite each other for engagement with the forward edge of the carton blank, and by 130

means of these notches the forward travel of the blank is arrested, these notches marking the limit of forward travel of the carton blank. Pieces of metal 93 partially traversing the space between the notches 92 are secured in the lower portions of those notches and curved downwardly from the openings of the notches, for a purpose to be described. The retaining arms 83 and 84 extend backwardly to a position adjacent the feeding roll 82, from which they receive the carton blank after its side flaps 39 and 40 have been folded in the flap-folding device above described, the action of the feed roll 82 carrying the carton forward to engagement with the notches 92. The carton when positioned between the retaining arms, upon the supporting arms and within the notches 92, occupies the afore-mentioned central position within the machine. Any suitable adhesive-applying device is employed, generally indicated by D in Figs. 1 and 4, and it is provided with a paste-applying roll 94 positioned above and slightly forward of the forward end 81 of the forming plate 74. As the carton blank B lies in the central position in the machine, its rear end flap 42, to which paste is to be applied, is positioned below the paste-applying roll 94. For the purpose of applying paste to the rear end flap 42, a striker 95 is employed having preferably the lenticular form illustrated in Figs. 1 and 4, in order that it may clear the feed roll 82. The striker is pivoted upon a pin 96 which extends through to the back of the machine (see Fig. 2), where it is rigidly connected with an arm 97 provided at its free end with a roller 98. A circular cam 99 is fixed upon the shaft 57 and is provided with a depression 100. The roller 98, riding upon the cam 99, engages the depression 100, thereby oscillating the pin 96 and the striker 95 into the position illustrated in full lines in Figs. 1 and 4, wherein the striker throws the rear end flap 42 of the carton blank upwardly into contact with the paste-applying roll 94. This action applies paste to the flap 42, leaving unpasted two portions 101 as shown in Fig. 12, for a purpose to be described. The rise of the roller 98 from the depression 100 lowers the striker 95 out of the path of forward travel of the succeeding carton blank and permits the pasted blank to resume the horizontal position.

When the carton blank B occupies the afore-mentioned central position within the machine, it receives the set of crayons which it is to infold. This set of crayons comprises one dropped from each of the throats 25 upon the rearward portion of the upper surface of the supporting plate 91. By reason of the thickness of the walls of the throats 25 (see Fig. 6), the crayons are in spaced relation to each other as they drop

upon the plate 91, and, as shown in Figs. 5 and 6, they are positioned a considerable distance back of the center of the machine. The relative terms "forward" and "backward" heretofore employed in this description referred to the travel of the carton blank B from the container 33 to the central position in the machine. These same terms will be used in this paragraph with relation to the movement of the crayons from the bottom of the magazine A to their position within the carton at the center of the machine. From their position below the bottom of the magazine, the set of crayons is moved forward by a push plate 102 (see Figs. 3, 5 and 6), which is actuated by power from the main shaft through any suitable mechanism—preferably that shown in the drawings, wherein a vertical rack 103, actuated by a cam wheel 104, rotates a pinioned shaft 105 which carries a fixed gear 106 meshing with a horizontal rack 107 secured to the rearward end of the push plate 102 by means of an arm 108, the rack 107 reciprocating in a channeled portion of the frame 20. The upper surface of the supporting plate 91 lies slightly above the upper edge of the folded side flap 39, and the action of the push plate 102 thrusts the set of crayons over the flap 39 and causes them to drop onto the bottom 34 of the carton blank B. The backward limit of travel of the push plate 102 is shown in Fig. 3, while its forward position is illustrated in Figs. 5 and 6.

Guide channels 109 for the push plate are formed upon the sides of the supporting plate 91, the metal of the supporting plate slightly overlapping the sides of the push plate from the rear of the supporting plate 91 to a point slightly forward of the forward face of the magazine A. From this last mentioned point the overlapping portions of the guide channels 109 approach each other, forming crayon guides 110 which are spaced from the crayon-bearing surface of the supporting plate 91 a distance just sufficient to admit of the reciprocation of the push plate 102 but not as great as the thickness of the crayons, the push plate being of lesser thickness than the crayons. The function of the crayon guides 110 is to bring the crayons into close relation with each other from the spaced relation they bear to each other as they are dropped from the magazine. In other words, as the push plate moves forwardly pushing a set of the crayons onto the carton blank, it passes beneath the crayon guides 110, which guides contact with the outer crayon on each end of the set and crowd the crayons toward each other until they assume the relation shown at the left of Fig. 6, wherein the total transverse length of the set of crayons equals the length of

the bottom 34 of the carton blank B. During the pushing forward of the set of crayons, therefore, the push plate contacts with the lower portions of the rearward ends of 5 the crayons in the set while the crayon guides 110 contact with the upper portions of the sides of the outer crayons of the set to crowd the crayons against each other as they are pushed forward by the push plate. 10 Hinged to the frame 20 as at 111 (see Figs. 1, 4, 6 and 7) is a cover plate 112, which traverse the supporting plate 91 and is spaced thereabove a distance slightly greater than the thickness of the crayons; a 15 spring-actuated latch 113 removably maintaining the cover plate in position. As shown in Figs. 5 and 6, the forward edge of the cover plate extends partially over the carton blank B as that blank lies in the central 20 position in the machine, and is slightly downbent, as at 114, to give the forward ends of the crayons a downward impulse as they are pushed out over the carton blank. To assist in the rapid positioning of the set 25 of crayons, the forward portion of the upper surface of the supporting plate 91 is downwardly beveled, as at 115. The action of the push plate 102 being rapid, it is necessary to provide means for alining all the 30 crayons of each set as they are dropped onto the carton blank, and for this purpose the stop 90 is provided; each crayon of the set contacts at its forward end with the stop 90 and all of the crayons are stopped in 35 alinement by it.

Below the center of the machine (see Figs. 1, 2, 3, 4, 5 and 7) a shaft 116 is horizontally journaled in the frame 20 and adapted to be oscillated through approximately 40 ninety degrees by means of an arm 117 fixed upon its rearward end and carried in a suitable cam 118 driven by the main shaft 22. Fixed upon the forward end of the shaft 116 is a bracket 119, carrying at its free end 45 a carton table 120 provided with end stops 121 and 122, the length of the table between the stops being just sufficient to receive the bottom 34 of the carton blank B and the transverse dimension of the table being 50 slightly less than the distance between the supporting arms 85 and 86. Adjacent the bottom of the bracket 119 are formed, on forward and rearward sides thereof, bracket arms 123 and 124, from the ends of which 55 protrude pins 125 and 126. Loosely journaled near their bottoms upon the pins 125 and 126 are a pair of clamping plates 127 and 128, which terminate at their upper ends approximately on a level with the upper extremities of the end stops 121 and 122. A spring member 129 tends normally to draw the clamping plates toward each other, their movement in this direction, however, being limited by detents 130 and 131 formed 60 upon the bracket 119. Alined fingers 132 and 133 are carried by and extend inwardly from the plates 127 and 128, respectively, terminating adjacent each other between the plates, and a wedge 134 journaled upon the shaft 116 is provided, which is adapted to enter between the fingers 132 and 133 to force the clamping plates 127 and 128 apart, the wedge being operated in any suitable manner by power from the main shaft 22, preferably through an arm 135 carrying at 65 its free end a roller 136 which travels upon a cam 137 borne by the main shaft. A support 138 (see Figs. 4 and 6) maintains the arms 83, 84 and 89 permanently in fixed relation with the frame of the machine. 70

A bearing 139 formed upon the frame 20 supports for vertical reciprocation an arm rod 140, to which are secured the supporting arms 85 and 86. A presser bracket 141, journaled upon the arm rod 140 for vertical reciprocation and having a guide 142 co-operating with a guide surface 143 upon the side of the bearing 139, carries at its upper end a presser 144, the presser being properly placed and of a length sufficient to traverse all of the crayons of one set as they lie positioned in the carton blank at the center of the machine. The vertical reciprocations of the arm rod 140 and the presser bracket 141 may be accomplished in any 75 suitable manner by means of power received from the main shaft 22. Preferably, however, they are actuated by a cam wheel, generally indicated at 145, the arm rod 140 carrying at its lower end a bifurcated guide 80 member 146 which engages opposite sides of the main shaft 22 to form a bearing for the lower end of the rod, there being a roller 147 upon the guide 146 which engages a cam channel 148 upon the wheel 145. 85 Upon its lower end the presser bracket 141 carries a roller 149, which engages a cam channel 150 in the wheel 145, the channels 148 and 150 being properly formed in the wheel 145 to accomplish the movements desired in the rod 140 and bracket 141. Secured preferably to the cover plate 112, and positioned over the forward portion of the cover 41 of the carton blank B as the blank 90 lies in the central position in the machine, is an arm 151 carrying two projections 152 adapted to engage the unpasted sections 101 of the rear end flap 42 of the carton blank during a part of the folding process to be described. Registering opposite each other 95 in the retaining arms 83 and 84 are two channels 153 cut into the inner surfaces of the arms and slanted from their lower extremities at an angle of approximately forty-five degrees from the horizontal and in the direction of the left hand side of the machine as viewed from the front. The lower extremities of these channels 153 register above the end stop 121 of the carton table 120 as that table stands in the position 100

105 110 115 120 125 130 135 140 145 150 155 160

illustrated in Fig. 4. Loosely carried by its ends in the channels 153 is a folding bar 154 (see Figs. 4 and 7) which is adapted, in certain positions of the carton blank during 5 the folding process, to be moved by the carton blank from the lower ends to the upper ends of the channels 153. After the passing of each carton blank in the folding process to be described, the force of gravity 10 turns the folding bar 154 to a position at the bottoms of the channels 153.

After the set of crayons has been placed upon the carton blank at the center of the machine, the presser 144 descends upon the 15 crayons to retain them in position on the blank, and at the instant it touches the crayons the supporting arms 85 and 86 descend into the dotted position illustrated in Fig. 5, the carton blank and the crayons being 20 held between the supporting arms 85 and 86 and the presser 144 during their descent. The action just described partially folds the carton blank and positions the blank and its set of crayons upon the carton table 25 120 and between the end stops 121 and 122. A more minute description of the folding process and other functions performed by the various parts will be made in the description of the operation of the machine. 30 Upon receiving the carton blank partially folded about its set of crayons, the bracket 119 with the parts carried thereby as previously described oscillates through approximately ninety degrees from the position 35 illustrated in Fig. 4 to that shown in Fig. 7, which performs further folding functions upon the carton. During this oscillation of the bracket 119 the carton is inclosed by the carton table 120, the end stops 121 and 122 40 and the clamping plates 127 and 128. Pivot- ed as at 155 (see Fig. 1) is a bell crank 156, which at one of its ends in any suitable manner receives power from the main shaft 22 to oscillate it. The other arm of the bell crank 45 extends upwardly and carries at its end a pair of fingers 157 (see Figs. 1, 4 and 7). As the bracket 119 oscillates into the position illustrated in Fig. 7, it descends about the fingers 157, which lie in a position be- 50 hind the partly folded carton. In this position of the parts the bell crank 156 is oscil- lated to move the fingers in a direction away from the shaft 116. This movement of the fingers 157 pushes the partly folded carton 55 blank into the adjacent end of a carton mag- azine 158 while at the same time completing the folding of the blank B into the carton C.

The magazine 158 (see Figs. 1, 2, 4 and 60 7) is secured in any suitable manner to the frame 20 and is provided with a cover 159. Adjacent the cover are two pivot pins 160 and 161 upon which are carried respectively bell cranks 162 and 163. The lower arms 65 164 and 165 of the bell cranks are joined

to a connecting rod 166, which is recipro- cated in an approximately horizontal direc- 70 tion by any suitable means driven from the shaft 22. The opposite ends of the bell cranks are of equal length and extend in the same direction from the pivots 160 and 161, and upon their extremities bear pivots 167 and 168, respectively, upon which is pivoted the cover 159. The reciprocation of the connecting rod 166 acts through the 75 bell cranks 162 and 163 to reciprocate the cover 159 continuously, the cover performing a tapping action upon the upper ends of the cartons C within the magazine 158 to insure the proper adhesion of the pasted 80 rear end flap 42 to the forward end piece 35.

Preferably, the forward face of the crayon magazine A is open and, for the purpose of preventing the escape of crayons from the front of the magazine and also 85 for the purpose of properly positioning them at the upper ends and adjacent the lower ends of the throats 25, two tapping bars 169 and 170 (see Figs. 1, 3 and 4) are positioned across the front of the magazine 90 A and are actuated by any suitable means deriving its power from the main shaft 22, the means preferably comprising a pivot shaft 171 (see Fig. 2) on the back of the machine journaled in bearings 172 and 173 95 upon the back of the magazine, carrying at its ends supporting arms 174 and 175, to which the ends of the tapping bars 169 and 170 are secured, the pivot shaft 171 being oscillated by means of a crank 176 fixed upon it and receiving power from the main shaft 22 through a cam (not shown) upon shaft 57. The action of the parts just described causes a reciprocation of the tapping bars 169 and 170 away from and against 100 the forward face of the magazine A, and operates to return to proper position any of the crayons which may by agitation have been caused to creep forward of the face of 105 the magazine.

In the operation of a machine, the cham- bers 24 being supplied with crayons to be packed and the container 33 being filled with the stack of carton blanks B, the ap- 110 plication of power to the pulley 21 rotates the feed roll 55. When the rubber segment 56 comes in contact with the lowermost blank in the container 33, that blank and generally if there is strong adhesion between the blanks, several of those above it, are 115 pushed forward by friction against the bevel 59 which separates the forward edges of the cartons, at the same time slightly lower- 120 ing them until the lowermost carton only passes beneath the detent 61 and is fed for- 125 ward to the rolls 58 and 58^a. These rolls, in conjunction with the rolls 68 and 68^a, feed the blank B to the flap-folding device illus- trated in detail in Fig. 14, where the blank 130 is bent upon the scored lines 50 and 51 by

the oscillation of the fingers 72 and 73 into the dotted position illustrated in Fig. 14. The feed roll 82 moves the carton blank forward from the flap-folding device to the center of the machine, where its forward edge engages the notches 92, contacting with the bottoms thereof. Simultaneously with the positioning of the blank in the center of the machine, the striker 95 elevates the rear end of the blank, bringing the rear end flap 42 into contact with the paste-applying roll 94 and applying paste upon the whole upper surface of the rear end flap, with the exception of the two sections 101; 10 the striker thereupon returning to its lower position out of the path of forward travel of blanks from the flap-folding device to the center of the machine. During the operation just described, a set of crayons has 15 been dropped from the magazine A upon the supporting plate 91, and upon the positioning of the blank B at the center of the machine the push plate 102 moves forward toward the center of the machine, pushing 20 before it one set of crayons, which drops over the upwardly folded flap 39, strikes against the stop 90 and rests in perfect alignment exactly upon the bottom 34 of the blank, the crayons being alined at their 25 rearward ends adjacent the scored line 44 of the carton blank and at their forward ends adjacent the scored line 46. The action of the cam 137 at this juncture advances the wedge 134 between the alined fingers 132 and 133, forcing apart at their upper ends the clamping plates 127 and 128. The presser 144 now descends upon the tops of the crayons on the carton to withhold them from casual dislodgment, whereupon the 30 presser and the supporting arms 85 and 86 descend until those arms assume the dotted positions illustrated in Fig. 5. This action carries forward the process of folding the carton blank, the side pieces 37 and 38 contacting with the shoulders 87 and 88, causing 35 a bending of the blank at right angles along the scored lines 44 and 46 and positioning the previously bent side flaps 39 and 40 directly over the end portions of the 40 crayons; in other words, folding the side pieces 37 and 38 and the side flaps 39 and 40 about opposite ends of the crayons. 45 A further folding action has also been had during the descent of the arms 85 and 86 and the presser 144 by reason of the metal pieces 50 93, which, lying in the path of the forward end piece 35, contact therewith and bend the carton blank upon the scored line 43 forming the forward end piece into a web 55 which becomes one side of the finished carton. 60 A still further folding action has been had during the descent of the arms 85 and 86 by reason of contact between the folding bar 154 and the rearward end piece 36, this 65 contact resulting in a fold of the blank upon the scored line 45. This last upward folding of the rear end piece 36 bends it into a web to form a side for the finished carton opposite that formed by the forward end 70 piece 35. The action of the presser 144 forces the blank, folded as described, into a position upon the carton table 120 and between the end stops 121 and 122, which end stops prevent the outward spring of the 75 folded end pieces 35 and 36. As soon as the partly folded blank assumes this position upon the carton table 120, the action of cam 137 withdraws wedge 134 from between the fingers 132, 133, allowing the spring 129 to 80 draw the clamping plates 127, 128 against the sides of the partly folded carton, this action clamping the carton and the crayons it contains in position upon the carton table and preventing any outward spring of the 85 folded side pieces 37 and 38 and their side flaps 39 and 40. By reason of the fact that the flap-folding device illustrated in Fig. 14 bent the side flaps 39 and 40 at an acute angle with the remainder of the carton 90 blank, those flaps at this point in the folding process assume a position directly over the ends of the crayons in the blank, the width of the presser 144 being such that its presence in contact with the upper sides of the 95 crayons does not interfere with the in-folding of the side flaps 39 and 40 above the ends of the crayons. The partly folded blank being now clamped in position upon the carton table 120, and being sufficiently 100 formed to constitute an open-topped carton, the action of cam 118 upon arm 117 and shaft 116 oscillates bracket 119 and the carton table and carton through approximately ninety degrees from the position shown in Fig. 4 to that in Fig. 7. At the beginning of this oscillation, that portion of the cover 41 of the blank adjacent the scored line 47 contacts with the folding bar 154 and moves that bar from the bottoms to the tops of the 110 channels 153, and the continued oscillation of the table bends the blank upon the scored line 47. A curved guide 177 (see Figs. 4 and 7) engages the cover 41, now folded, and retains the cover in folded position upon the tops of the crayons, following its initial fold by bar 154. When the oscillation of the bracket 119 and the table 120 has been completed, the carton is fully folded, with the exception of the pasted rear end flap 120 42 which, during the descent of the carton blank from the center of the machine to the carton table, was withheld from contact with the guide 114 and the free end of the presser 144 by means of the projections 152, 125 these projections contacting with the un-pasted sections 101 of the rear end flap 42. With relation to the table 120, the fingers 157, when the table is in the position illustrated in Fig. 7, assume initially the posi- 130

tion occupied with relation to the table by the supporting arms 85 and 86 when the table is in the upright position illustrated in Figs. 4 and 5, and when the supporting arms 5 are in the lowered or dotted position illustrated in Fig. 5. In other words, the fingers 157 assume a position behind the partly formed carton. From this position the fingers 157 are moved forwardly, pressing the 10 carton into the adjacent end of the carton magazine 158, which registers with the carton table 120. This action of the fingers 157 completes the folding of the carton by bending the blank upon the scored line 48, 15 and, the internal dimensions of the magazine being exactly those of the finished carton, the rear end flap 42 is not only bent into proper position but is pressed against the outer surface of the forward end piece 35, 20 in order that the paste upon the rear end flap 42 may cause adhesion between it and the forward end piece. The action of the fingers 157 in pressing the carton forward and completing its folding simultaneously 25 pushes forward within the magazine all the cartons contained therein, and during this pushing movement of the whole body of finished cartons in the magazine 158 the cover 159 is elevated, the action in ordinary 30 practice being very rapid, and the return of the cover to a position in contact with all the finished cartons in the magazine resulting in a tapping upon the outer unpasted surface of the rear end flap 12 of each finished carton, in order to maintain those flaps in proper adhering position with relation to the forward end piece 35 until the 35 magazine has been filled.

In the construction of the carton magazine 40 158, that end thereof into which the cartons are pushed by the fingers 157 is, as stated above, of a size adapted to fit closely about the carton and a fixed removable cover 180 (see Fig. 4) is provided for a portion of 45 this end of the magazine, the tapping cover 159 extending only to the fixed cover 180. The length of the fixed cover 180 is preferably sufficient to cover a plurality of cartons, and an important function is performed by this fixed cover in that the 50 freshly pasted rear end flaps 42 are held against the forward end pieces 35 of the cartons beneath the fixed cover for a time sufficient to place adhesion between them well 55 under way; and not until such adhesion has been well advanced do the cartons C move in the magazine 158 beneath the cover 159 and receive its tapping action.

The rearward edge of the cover plate 112 60 contacting with the set of crayons just above that pushed forward by the push plate 102 prevents the forward feeding from the throats 25 of the next-to-the-bottom set of crayons in the throats, the thickness of the 65 push plate 102 being less than that of the

crayons which it touches. During the travel of the carton blank onward from its position in the center of the machine to the carton magazine 158, the push plate 102 is reciprocated to the position illustrated in Fig. 3, 70 wherein its forward crayon-contacting edge is drawn back of the rear ends of the crayons in magazine A, allowing another set of crayons to drop from the throats 25 upon the supporting plate 91. 75

In the accompanying drawings and in the foregoing description is set forth the preferred embodiment of our invention, but it is obvious that one skilled in the art may make modifications thereof without departing 80 from the spirit of the invention.

What we claim is:

1. The combination of means for supplying carton blanks, a series of devices for positioning one article from each of said devices upon a single carton blank to form a set of such articles, means for supplying articles of different characteristics to each of said series of devices, and apparatus for folding the blank about the set of articles 90 to form a carton. 85

2. The combination of a container for carton blanks, a series of guide-ways for positioning one article from each thereof upon a single blank to form a set, separate hoppers 95 for supplying articles of different characteristics to said guideways, and apparatus for folding the blank about the set of articles to form a carton.

3. The combination of a container for 100 carton blanks, mechanism for selecting a single blank from said container, a plurality of separate means for guiding articles onto the blank so selected to form a set, separate means for supplying articles of different characteristics to said guiding means, and apparatus for folding the blank about the set of articles. 105

4. The combination of a container for 110 carton blanks, mechanism for selecting a single blank from said container, a plurality of separate chutes for guiding articles onto the blank so selected to form a set of articles of different characteristics, separate 115 magazines for supplying articles of different characteristics to said chutes, and apparatus for folding the blank about the set of articles to form a carton.

5. The combination of a container for 120 carton blanks, mechanism for selecting blanks one at a time from said container, a plurality of separate chutes for guiding articles onto the blanks so selected to form a set on each blank, a magazine for each of 125 said chutes to supply articles thereto, apparatus for folding the blanks about the articles positioned thereon, a magazine for holding the cartons so formed, and means for placing the formed cartons in said magazine. 130

6. The combination of a container for carton blanks having side flaps, mechanism for selecting a single blank from said container, means for upturning the side flaps of the selected blank, apparatus for applying adhesive to the selected blank, a plurality of chutes for guiding a predetermined combination of articles of different characteristics onto the blank so selected, separate magazines for supplying articles of different characteristics to said chutes, and mechanism for folding the blank about the set of articles positioned thereon to form a carton.

7. The combination of a container for carton blanks, mechanism for selecting a single blank from said container, means for guiding a plurality of articles having different characteristics to said blank and simultaneously depositing them thereon, and a separate device for containing the articles of each characteristic and supplying said articles to said guiding means.

8. The combination of a container for carton blanks, apparatus for folding a blank into a carton, means for supporting a blank over the folding apparatus, mechanism for selecting a single blank from the container and placing it upon the supporting means, devices for positioning a set of articles to be packed upon the supported blank prior to the action of the folding apparatus, a magazine for articles to be packed comprising a plurality of separate chambers for the articles, throats communicating with said chambers and converging to a level just above the article-positioning mechanism, and devices located at the junctures of the chambers and throats for agitating the articles in the chambers.

9. The combination of a container for carton blanks, a magazine for articles to be packed, apparatus for selecting a single blank from the container, supporting means for the selected blank, devices for selecting a set of the articles and simultaneously positioning the articles of the set upon the supported blank, a carton table beneath the supporting means, a magazine for folded cartons, a presser for retaining the set of articles in position upon the supported blank, said supporting means and presser being movable to position the blank and articles upon the carton table, devices for partially folding the carton blank during said movement of the supporting means and presser, and apparatus for transferring the partially folded blank from the carton table to the carton magazine, said carton magazine having means coöperating with said transferring apparatus to complete the folding of the carton blank.

10. The combination of a container for carton blanks having side flaps, a magazine for articles to be packed, apparatus for selecting a single blank from the container, devices for folding the side flaps of the

selected blank, supporting means for the selected blank, mechanism for applying an adhesive to the selected blank, apparatus for selecting a set of the articles and positioning it upon the supported blank, a carton table beneath the supporting means, a magazine for folded cartons, a presser for retaining the set of articles in position upon the supported blank, said supporting means and presser being movable to position the blank and articles upon the carton table, devices for partially folding the carton blank during said movement of the supporting means and presser, clamping devices for securing the partially folded blank upon the carton table, apparatus for transferring the partially folded blank from the carton table to the carton magazine, a fixed cover portion for said carton magazine coöperating with said transferring apparatus to complete the folding of the carton blank, and a reciprocating cover portion for the carton magazine for securing the adhesive bearing portion of the carton blank to the body of the folded blank.

11. In a carton filling and forming machine, the combination with apparatus for feeding carton blanks having side flaps, of a movable device for simultaneously making throughout its length in one of said flaps a preliminary fold about a forming plate adapted to determine the line of such fold, and means for making a second fold in said flap parallel with said preliminary fold.

12. In a carton filling and forming machine, the combination with apparatus for feeding carton blanks having side flaps, of mechanism for folding said side flaps, comprising fingers mounted on stationary pivots located near the line on which said flaps are to be folded and adapted to contact with the side flaps and bend them with relation to the body of the blank, and a forming plate coöperating with the fingers to determine the line of bend.

13. In a carton filling and forming machine, the combination with apparatus for feeding carton blanks having side flaps, of mechanism for folding said side flaps, comprising a platen positioned to receive a blank from the feeding apparatus, a forming plate positioned above the platen, and fingers normally positioned without the path of travel of the blank and adapted to swing about stationary pivots located near the edges of said forming plates to contact with the blank to fold the side flaps about the forming plate.

14. In a carton filling and forming machine, the combination with apparatus for feeding carton blanks having side flaps, of mechanism for folding said side flaps, comprising a platen adapted to receive a carton blank from the feeding apparatus, a forming plate having forming edges registering

with the inner edges of the side flaps, movable fingers pivoted near said forming edges and adapted to contact with the side flaps and fold them about the forming edges of the plate, and mechanism for operating said fingers.

15. In a carton filling and forming machine, the combination with apparatus for feeding carton blanks having side flaps, of mechanism for folding said side flaps, comprising a platen adapted to receive a carton blank from the feeding apparatus, a forming plate having forming edges registering with the inner edges of the side flaps, movable fingers adapted to swing about pivots near said forming edges to contact with the side flaps and fold them about the forming edges of the plate, and mechanism for operating said fingers, said fingers being positioned normally out of the path of travel of the carton blank.

16. In a carton filling and forming machine, the combination with apparatus for feeding carton blanks having side flaps, of mechanism for folding said side flaps, comprising a forming plate positioned over the blank as it comes from the feeding apparatus and having forming edges registering with the inner edges of the side flaps, pivoted fingers normally positioned below the path of travel of the blank and adapted to contact with the side flaps, and devices for oscillating the fingers about pivotal centers near the folding line of said blanks into contact with the side flaps and for advancing said side flaps to a position above the forming edges of the plate.

17. In a carton filling and forming machine, the combination with apparatus for feeding carton blanks having side flaps, of mechanism for folding said side flaps, comprising a platen of approximately the length of the side flaps and adapted to receive the blank from the feeding apparatus, a forming plate positioned above the platen and having forming edges registering with the inner edges of the side flaps and of a length approximating that of the side flaps, folding fingers pivoted at the sides of the platen and beneath the blank-receiving surface thereof, said fingers being of a length approximating that of the side flaps, and mechanism for oscillating the fingers into contact with the side flaps and for further oscillating the fingers to fold the side flaps upon their inner edges and about the forming edges of the forming plate.

18. In a carton filling and forming machine, the combination with apparatus for feeding carton blanks having side flaps, of mechanism for folding said side flaps, comprising a platen of approximately the length of the side flaps and adapted to receive the blank from the feeding apparatus, a forming plate positioned above the platen and

having forming edges registering with the inner edges of the side flaps and of a length approximating that of the side flaps, folding fingers pivoted at the sides of the platen and beneath the blank-receiving surface thereof, said fingers being of a length approximating that of the side flaps, and mechanism for oscillating the fingers into contact with the side flaps and for further oscillating the fingers to fold the side flaps upon their inner edges and about the forming edges of the forming plate and into contact with the upper surface of said plate.

19. In a carton filling and forming machine, the combination with apparatus for feeding carton blanks having side flaps, of mechanism for folding said side flaps, comprising a platen of approximately the length of the side flaps and adapted to receive the blank from the feeding apparatus, a forming plate positioned above the platen and having forming edges registering with the inner edges of the side flaps and of a length approximating that of the side flaps, folding fingers pivoted at the sides of the platen and beneath the blank-receiving surface thereof, said fingers being of a length approximating that of the side flaps, and mechanism for oscillating the fingers into contact with the side flaps and for further oscillating the fingers to fold the side flaps upon their inner edges and about the forming edges of the forming plate, said oscillating mechanism comprising an oscillating pivot bar and a pair of links pivoted at their lower ends to said bar and each pivoted at its upper end to one of said fingers.

20. In a carton filling and forming machine, the combination with apparatus for feeding carton blanks having side flaps, of mechanism for folding said side flaps, comprising pivoted fingers adapted to contact with the side flaps and bend them with relation to the body of the blank, a forming plate co-operating with the fingers to determine the line of bend, and devices for actuating said fingers after each action of the feeding apparatus, to swing them about pivots adjacent said line of bend.

21. In a carton filling and forming machine, the combination with apparatus for feeding carton blanks having side flaps, of mechanism for folding said side flaps at an angle with the body of the blank more acute than that desired in the finished carton, and means for folding said blanks along lines parallel with the lines of said first mentioned folds to bring the portion first folded into contact with the contents of the carton being formed.

22. In a carton filling and forming machine, the combination with apparatus for feeding carton blanks having side flaps, of mechanism for folding said side flaps at an angle with the body of the blank more

- acute than that desired in the finished carton, comprising a forming plate having forming edges registering with the inner edges of the side flaps, the surfaces meeting at said forming edges making with each other the said more acute angle, and devices for bending the blank about the forming edges and into contact with the surfaces meeting at said edges.
23. The combination with apparatus for feeding carton blanks having side flaps, of mechanism adapted to receive a carton blank from said feeding apparatus and fold said side flap into an acute angle with relation to the body of the blank and means for folding said blanks along lines parallel with the lines of said first mentioned fold to bring the portion first folded into contact with the contents of the carton being formed.
24. The combination with apparatus for feeding carton blanks having side flaps, of mechanism adapted to receive a carton blank from said feeding apparatus and fold said side flaps into an acute angle with relation to the body of the blank, comprising a platen, a forming plate spaced above said platen and having forming edges registering with the inner edges of the side flaps, the surfaces of said forming plate meeting at said forming edges making with each other an acute angle, and devices for bending the carton blank about the forming edges of the plate and into contact with the surfaces of the plate meeting at said forming edges.
25. In a carton filling and forming machine, the combination of supporting arms, apparatus for feeding forward singly carton blanks having side flaps, mechanism for folding said side flaps, devices for positioning the blank upon the supporting arms after the side flaps have been folded, and means for applying an adhesive to the rearward portion of the blank after it is so placed.
26. In a carton filling and forming machine, the combination of supporting arms, apparatus for feeding forward singly carton blanks having side flaps, mechanism for folding said side flaps, devices for positioning the blank upon the supporting arms after the side flaps have been folded, and means for applying an adhesive to the rearward portion of the blank after it is so placed, comprising an adhesive-applying roll and a striker adapted to force the rearward portion of the blank into contact with the applying roll.
27. In a carton filling and forming machine, the combination of supporting arms, apparatus for feeding forward singly carton blanks having side flaps, mechanism for folding said side flaps, devices for positioning the blank upon the supporting arms af-
- ter the side flaps have been folded, and means for applying adhesive to the rearward portion of the blank after it is so placed, comprising an adhesive-supplying roll and a striker normally out of the path of movement of the blank and adapted to force the rearward portion of the blank into contact with the applying roll.
28. In a carton filling and forming machine, the combination of supporting arms, apparatus for feeding forward singly carton blanks having side flaps, mechanism for folding said side flaps, devices for positioning the blank upon the supporting arms after the side flaps have been folded, and means for applying an adhesive to the rearward portion of the blank after it is so placed, comprising an applying roll positioned adjacent the rearward end of the blank, an oscillating striker adapted to force the rearward end of the blank into contact with the applying roll, and actuating means for the striker operable as the blank assumes position upon the supporting arms.
29. In a carton filling and forming machine, the combination of supporting arms, apparatus for feeding forward singly carton blanks having side flaps, mechanism for folding said side flaps, devices for positioning the blank upon the supporting arms after the side flaps have been folded, and means for applying an adhesive to the rearward portion of the blank after it is so placed, comprising an adhesive-applying roll positioned above the rearward portion of the blank, a striker positioned below the rearward portion of the blank and normally out of the path of travel thereof, and actuating means operating upon the striker to bring it into contact with the rearward portion of the carton blank and to cause it to carry said rearward portion into contact with the applying roll.
30. In a carton filling and forming machine, the combination of supporting arms, mechanism for feeding a carton blank to said supporting arms, an adhesive-applying roll adjacent the rearward portion of the blank as it lies upon the supporting arms, and apparatus for striking said rearward portion against the applying roll.
31. In a carton filling and forming machine, the combination of supporting arms for a carton blank, apparatus for feeding a carton blank to said supporting arms, an adhesive-applying member adjacent the rearward extremity of the blank as it lies upon the supporting arms, and a device for striking the rearward portion of the blank against the adhesive-applying member.
32. In a carton filling and forming machine, the combination of a plurality of separated supporting arms, mechanism for positioning a carton blank thereon, means

for supplying the blank with a set of articles to be packed, a receiving table, and means for moving said arms on opposite sides of said receiving table to transfer said blank with the set of articles thereunder to said table.

33. In a carton filling and forming machine, the combination of supporting arms, mechanism for positioning a carton blank thereon, and means for supplying the blank with a set of articles to be packed, comprising a magazine for holding a quantity of the articles, a supporting member upon which the set of articles to be packed is positioned from the magazine by force of gravity, said member terminating forwardly adjacent the carton blank, and a push plate adapted to contact with the rear ends of the articles of the set and move the set forwardly to a position upon the carton blank, and stationary means for longitudinally positioning said articles relative to said blank.

34. In a carton filling and forming machine, the combination of supporting arms, mechanism for positioning a carton blank thereon, and means for supplying the blank with a set of articles to be packed, comprising a supporting plate terminating forwardly adjacent the blank, a magazine for articles to be packed adapted to deliver one set of articles at a time by gravity upon the supporting plate and positioned above the rearward end thereof, a push plate resting upon the article-receiving surface of the supporting plate, adapted to contact with the rearward extremities of the articles of the set and move the set forwardly into position upon the blank and a stationary plate adapted to limit the movement of said articles.

35. In a carton filling and forming machine, the combination of supporting arms for a carton blank, mechanism for positioning a carton blank upon the supporting arms, a supporting plate having its forward termination adjacent the supporting arms, a magazine for articles to be packed positioned above the rearward portion of said supporting plate and adapted to deposit a set of articles upon said supporting plate in spaced relation to each other, a reciprocating push plate adapted to carry said set forward to a position upon the carton blank, and side guides spaced from the set-supporting surface of the supporting plate a greater distance than the thickness of said push plate and a lesser distance than the thickness of one of said articles to be packed, said push plate being of lesser thickness than one of said articles to be packed and said side guides being adapted to crowd the articles of the set being pushed into close association prior to their positioning upon the blank.

36. In a carton filling and forming ma-

chine, the combination of supporting arms, mechanism for positioning a carton blank upon said supporting arms, a supporting plate having its forward termination adjacent the blank upon the arms, a magazine for articles to be packed adapted to deposit one set of said articles at a time upon the rearward portion of said supporting plate by gravity, the articles of the set deposited being in spaced relation to each other, side guides for the set of articles formed upon the sides of the supporting plate, spaced therefrom a lesser distance than the thickness of one of the articles of the set and converging at their forward ends, and a reciprocating push plate adapted to move the set of articles deposited from the magazine forwardly upon the supporting plate between the side guides and position the set on the blank upon the supporting arms, the thickness of said push plate adapting it to move between said side guides and said supporting plate.

37. In a carton filling and forming machine, the combination of supporting arms, mechanism for positioning a carton blank thereupon, a magazine for articles to be packed comprising chambers for said articles, a discharging throat for each of said articles, each of said throats being adapted to deposit one article therefrom to form a set of articles, and said throats converging at their discharge ends to separate the articles of the set deposited from each other a distance equal to the thickness of the walls of said throats, and devices for moving the articles of the set deposited into close association and placing them upon the carton blank on the supporting arms.

38. In a carton filling and forming machine, the combination of a magazine for articles to be packed, a supporting plate positioned beneath said magazine and adapted to receive a set of articles therefrom, the articles of the set when deposited from the magazine being spaced from each other, supporting arms for a carton blank positioned at a lower level than that of the set-receiving surface of the supporting plate, mechanism for positioning a carton blank upon the supporting arms, the forward portion of said supporting plate terminating above one side of the carton blank upon the supporting arms, side guides upon said supporting plate, and a reciprocating push plate adapted to move the set of articles forwardly upon the supporting plate between the side guides and onto the carton blank upon the supporting arms and stationary means for limiting the forward movement of said articles.

39. In a carton filling and forming machine, the combination of a magazine for articles to be packed, a supporting plate beneath said magazine adapted to receive a

set of articles to be packed therefrom, supporting arms forward of said magazine and adapted to support a carton blank upon a level below that of the set-receiving surface of the supporting plate, mechanism for feeding single carton blanks having side flaps to said supporting arms, a device for folding said side flaps while they are being fed to the supporting arms, said side flaps terminating upwardly when folded at a point approximately level with the set-receiving surface of the supporting plate, a cover for the forward end of said supporting plate and overreaching the forward terminus thereof, said cover being downbent at its forward extremity to form an article guide and being spaced above the path of movement of the articles, and a push plate adapted to move a set of articles to be packed forwardly upon the supporting plate from the point of deposit from the magazine to a position beyond the forward terminus of the push plate and onto the carton blank upon the supporting arms.

40. In a carton filling and forming machine, the combination of supporting arms, mechanism for positioning a carton blank thereupon, a supporting plate terminating above the blank upon the supporting arms, a magazine adapted to deposit a set of articles to be packed upon the rearward portion of said supporting plate, an article guide above said supporting plate overreaching the forward terminus thereof and being downbent at its forward extremity to form an article guide, a push plate adapted to project the deposited set of articles forward from the forward terminus of the supporting plate above and onto the carton blank, and an alining guide positioned above the carton blank as it lies on the supporting arms and transversely of the path of forward movement of the set of articles.

41. In a carton filling and forming machine, the combination of supporting arms, mechanism for positioning a carton blank thereupon, a supporting plate terminating above the blank upon the supporting arms, a magazine adapted to deposit a set of articles to be packed upon the rearward portion of said supporting plate, an article guide above said supporting plate overreaching the forward terminus thereof and being downbent at its forward extremity to form an article guide, a push plate adapted to project the deposited set of articles forward from the forward terminus of the supporting plate above and onto the carton blank, and an alining guide positioned above the carton blank as it lies on the supporting arms and transversely of the path of forward movement of the set of articles, said article guide contacting with the set during its forward movement to give the articles thereof a downward trend as they pass from the

forward terminus of the supporting plate, and said alining guide being of a length sufficient to traverse the path of forward travel of each article in the set.

42. In a carton filling and forming machine, the combination of supporting arms, mechanism for feeding carton blanks having side flaps to said supporting arms, a device for folding said side flaps during said feeding, retaining arms for maintaining said side flaps folded while the carton blank is upon the supporting arms, mechanism for depositing a set of articles to be packed upon said carton blank while it is on said supporting arms and means for further folding said side flaps to bring the part first folded into contact with said articles.

43. In a carton filling and forming machine, the combination of separated movable supporting arms, mechanism for feeding carton blanks singly thereto, apparatus for positioning a set of articles to be packed upon the blank upheld by the supporting arms, a movable presser adapted to contact with the set of articles upon the blank, and a carton table positioned below the supporting arms and intermediately thereof, said presser and supporting arms being adapted to carry the blank and the set of articles positioned thereon downwardly to said carton table.

44. In a carton filling and forming machine, the combination of separated movable supporting arms, mechanism for feeding carton blanks singly thereto, apparatus for positioning a set of articles to be packed upon the blank upheld by the supporting arms, a movable presser adapted to contact with the set of articles upon the blank, a carton table positioned below the supporting arms and intermediately thereof, said presser and supporting arms being adapted to carry the blank and the set of articles positioned thereon downwardly to the carton table, and devices contacting with the blank during said descent to partially fold the blank about the articles.

45. In a carton filling and forming machine, the combination of movable supporting arms, mechanism for feeding carton blanks singly thereto, apparatus for positioning a set of articles to be packed upon the blank upheld by the supporting arms, a movable presser adapted to contact with the set of articles upon the blank, a carton table positioned below the supporting arms, said presser and supporting arms being adapted to carry the blank and the set of articles positioned thereon downwardly to the carton table, and devices contacting with the blank during said descent to partially fold the blank about the articles, comprising retaining arms, shoulders upon said retaining arms positioned in the path of descent of the sides of the carton blank, projecting

pieces secured to said retaining arms and positioned in the path of descent of the forward end of the carton blank, and a folding bar carried by the retaining arms and disposed in the path of descent of the rearward portion of the blank.

46. In a carton filling and forming machine, the combination of movable supporting arms, fixed retaining arms spaced from each other, mechanism for feeding carton blanks singly upon the supporting arms and between the retaining arms, apparatus for positioning a set of articles to be packed upon the blank fed, a movable presser adapted to contact with the set of articles upon the blank, a carton table positioned below the supporting arms and provided with end stops, clamping plates upon opposite sides of said table, said presser and supporting arms being adapted to carry the blank and the set of articles positioned thereon downwardly to said carton table and between said end stops and said clamping plates, and devices for partially folding the carton blank during said descent.

47. In a carton filling and forming machine, the combination of movable supporting arms, fixed retaining arms spaced from each other, mechanism for feeding carton blanks singly upon the supporting arms and between the retaining arms, apparatus for positioning a set of articles to be packed upon the blank fed, a movable presser adapted to contact with the set of articles upon the blank, a carton table positioned below the supporting arms and provided with end stops, clamping plates upon opposite sides of said table, said presser and supporting arms being adapted to carry the blank and the set of articles positioned thereon downwardly to said carton table and between said end stops and said clamping plates, and devices for partially folding the carton blank during said descent, said end stops and clamping plates being positioned to retain the folded portions of the blank in folded position.

48. In a carton filling and forming machine, the combination of movable supporting arms, fixed retaining arms spaced from each other, mechanism for feeding carton blanks singly upon the supporting arms and between the retaining arms, apparatus for positioning a set of articles to be packed upon the blank fed, a movable presser adapted to contact with the set of articles upon the blank, a carton table positioned below the supporting arms and provided with end stops, clamping plates upon opposite sides of said table, said presser and supporting arms being adapted to carry the blank and the set of articles positioned thereon downwardly to said carton table and between said end stops and said clamping plates, and devices for partially folding the

carton blank during said descent, comprising shoulders upon said retaining arms positioned in the paths of descent of the sides of the carton blank, projecting pieces secured to said retaining arms and positioned in the path of descent of the forward end of the carton blank, and a folding bar carried by the retaining arms and disposed in the path of descent of the rearward portion of the blank.

49. In a carton filling and forming machine, the combination of movable supporting arms, fixed retaining arms spaced from each other, mechanism for feeding carton blanks singly upon the supporting arms and between the retaining arms, apparatus for positioning a set of articles to be packed upon the blank fed, a movable presser adapted to contact with the set of articles upon the blank, a carton table positioned below the supporting arms and provided with end stops, clamping plates upon opposite sides of said table, said presser and supporting arms being adapted to carry the blank and the set of articles positioned thereon downwardly to said carton table and between said end stops and said clamping plates, and devices for partially folding the carton blank during said descent, comprising shoulders upon said retaining arms positioned in the paths of descent of the sides of the carton blank, projecting pieces secured to said retaining arms and positioned in the path of descent of the forward end of the carton blank, and a folding bar carried by the retaining arms and disposed in the path of descent of the rearward portion of the blank, the said end stops and clamping plates being positioned to retain the folded portion of the blank in folded position.

50. In a carton filling and forming machine, the combination of movable supporting arms, mechanism for feeding a single carton blank to said supporting arms, apparatus for positioning a set of articles to be packed upon the fed blank, an oscillating carton table below said supporting arms, means coöperating with the supporting arms to carry the blank and the set of articles downwardly onto the carton table, devices operating upon the blank during said descent to partially fold it, including a shiftable folding bar lying in the path of descent of the rearward end piece of the blank, and means for oscillating said carton table, said shiftable bar being movable by the partially folded blank during the oscillation of the table to position it in the path of movement of the cover portion of the blank.

51. In a carton filling and forming machine, the combination of an oscillating carton table, means for positioning a partially folded carton blank bearing a set of articles

to be packed thereupon when the table is at one end of its path of oscillation, a carton magazine having its receiving end positioned at the other end of the path of oscillation of the carton table, means coöperating with the carton table to retain the partially folded blank and set of articles thereon, a guide for retaining in position the folded portions of the carton blank during oscillation of the table, mechanism for oscillating the table, and devices coöperating with the receiving end of the magazine for removing the partially folded carton from the table, completing the folding thereof and positioning the carton formed within the carton magazine.

52. In a carton filling and forming machine, the combination of an oscillating carton table, means for positioning a partially folded carton blank bearing a set of articles to be packed thereupon when the table is at one end of its path of oscillation, a carton magazine having its receiving end positioned at the other end of the path of oscillation of the carton table, means coöperating with the carton table to retain the partially folded blank and set of articles thereon, a guide for retaining in position the folded portions of the carton blank during oscillation of the table, mechanism for oscillating the table, and devices coöperating with the receiving end of the magazine for removing the partially folded blank from the table, completing the folding thereof and positioning the carton formed within the carton magazine, comprising movable fingers before which the partially folded carton is positioned during the oscillation of the table, said fingers being adapted to contact with the bottom of the carton blank and push the blank and its contents into the carton magazine, and a fixed cover portion upon the receiving end of the carton magazine lying in the path of movement of the unfolded portion of the carton blank during its passage from the table into the magazine.

53. In a carton forming and filling machine, the combination of mechanism for applying an adhesive to the rear end flap of a carton blank, apparatus for positioning a set of articles to be packed upon the blank, means for completing the folding of said carton blank about the articles to be packed with the exception of said rear end flap, a carton magazine, apparatus for forcing the partially folded blank into the receiving end of said magazine, and a fixed cover portion upon the receiving end of said magazine lying in the path of movement of said rear end flap and adapted to fold the flap upon the body of the partially folded blank.

54. In a carton forming and filling machine, the combination of mechanism for applying an adhesive to the rear end flap of a carton blank, apparatus for position-

ing a set of articles to be packed upon the blank, means for completing the folding of said carton blank about the articles to be packed with the exception of said rear end flap, a carton magazine, apparatus for forcing the partially folded blank into the receiving end of said magazine, and a fixed cover portion upon the receiving end of said magazine lying in the path of movement of said rear end flap and adapted to fold the flap upon the body of the partially folded blank and retain said rear end flap in folded position during its passage beneath said fixed cover portion.

55. In a carton filling and forming machine, the combination of a carton magazine, means for applying an adhesive to the rear end flap of a carton blank, apparatus for positioning a set of articles to be packed upon said blank and forming said blank into a carton about the articles with the exception of said rear end flap, and movable fingers adapted to receive the partially folded carton blank, project it into said carton magazine, and move forwardly within the carton magazine all cartons contained therein.

56. In a carton filling and forming machine, the combination of a carton magazine, apparatus for applying an adhesive to the rear end flap of a carton blank, mechanism for positioning a set of articles to be packed upon said blank and for folding the blank into a carton about the articles with the exception of said rear end flap, means for projecting the partially folded carton blank into the receiving end of said carton magazine, and a fixed cover portion for the receiving end of said carton magazine lying in the path of projection of said adhesive-bearing rear end flap and forming with the body of said magazine a receiving aperture closely fitting the formed carton.

57. In a carton filling and forming machine, means for applying an adhesive to the rear end flap of a carton blank, positioning a set of articles to be packed upon the blank and forming the blank into a carton about the articles with the exception of said adhesive-bearing rear end flap, a carton magazine adapted to receive the formed carton and to complete the forming thereof by folding said rear end flap into a position wherein its adhesive-bearing surface contacts with the body of the formed carton, a movable cover portion for said carton magazine, and means for reciprocating said cover portion away from and against the folded rear end flaps of the formed cartons in the magazine.

58. In a carton filling and forming machine, the combination of movable spaced supporting arms, apparatus for feeding a single carton blank to said supporting arms including means for folding the side flaps thereof, retaining members contacting with

- the folded side flaps of the carton blank while it lies upon the supporting arms, apparatus for positioning a set of articles to be packed upon the carton blank on the arms, a carton table positioned below the supporting arms and adapted to stand between them after their movement, end stops upon the carton table, a movable presser coöperating with said supporting arms to carry the carton blank and set of articles downwardly onto the carton table, mechanism for folding the sides of the carton blank during said descent, the end stops of said table retaining two of the folded sides of said blank
- 10 in folded position, movable clamping plates upon opposite sides of said table, a spring normally drawing said clamping plates together, and apparatus for forcing said clamping plates apart during the positioning of the blank upon the carton table and for allowing them to approach each other following the positioning of the blank upon the carton table.
59. In a carton filling and forming machine, the combination of movable spaced supporting arms, apparatus for feeding a single carton blank to said supporting arms including means for folding the side flaps thereof, retaining members contacting with the folded side flaps of the carton blank while it lies upon the supporting arms, apparatus for positioning a set of articles to be packed upon the carton blank on the arms, a carton table positioned below the supporting arms and adapted to stand between them after their movement, end stops upon the carton table, a movable presser coöperating with said supporting arms to carry the carton blank and set of articles downwardly onto the carton table, mechanism for folding the sides of the carton blank during said descent, the end stops of said table retaining two of the folded sides of said blank in folded position, movable clamping plates upon opposite sides of said table, a spring normally drawing said clamping plates together, and apparatus for forcing said clamping plates apart during the positioning of the blank upon the carton table
- 40 and for allowing them to approach each other following the positioning of the blank upon the carton table, comprising alined fingers terminating adjacent each other and projecting toward each other from adjacent sides of said clamping plates, a wedge adapted to enter between said alined fingers, and a movable cam operating said wedge.
60. In a carton filling and forming machine, the combination of an oscillating bracket, a carton table carried by the bracket, end stops upon the carton table, side clamping plates carried by the bracket terminating at their upper extremities upon opposite sides of the surface of said carton table and protruding thereabove, a spring normally

drawing the upper ends of said clamping plates toward each other, stops upon the bracket limiting the spring actuated travel of the clamping plates, alined fingers protruding toward each other from adjacent sides of the clamping plates, a cam-actuated wedge adapted to enter between said fingers and separate the clamping plates at intervals, and mechanism for positioning a partially folded carton blank and a set of articles therein upon said carton table, the wedge being adapted to recede from between the alined fingers after said positioning of the carton blank and articles.

61. In a carton filling and forming machine, the combination with carton filling and forming mechanism, of a source of supply for said filling mechanism, comprising a magazine containing chambers for articles to be packed and having feeding throats communicating with the lower portions of said chambers, and an agitating roller forming a portion of the bottom of each of said chambers at the juncture of the chamber and throat and rotating in contact with the articles in the chamber.

62. In a carton filling and forming machine, the combination with carton filling and forming mechanism, of a source of supply for said filling mechanism, comprising a magazine containing chambers for articles to be packed and having feeding throats communicating with the lower portions of said chambers, an agitating roller forming a portion of the bottom of each of said chambers at the juncture of the chamber and throat and rotating in contact with the articles in the chamber, and mechanism for rotating said rollers to cause their bottom-forming portions to move in a direction from the chamber toward the throat.

63. In a carton filling and forming machine, the combination with carton filling and forming mechanism, of a source of supply for said filling mechanism comprising a magazine containing chambers for articles to be packed and having feeding throats communicating with the lower portions of said chambers, and an agitating roller forming a portion of the bottom of each of said chambers at the juncture of the chamber and throat and rotating in contact with the articles in the chamber, each of said rollers having a longitudinal notch therein.

64. In a carton filling and forming machine, the combination with carton filling and forming mechanism, of a source of supply for said filling mechanism comprising a magazine containing chambers for articles to be packed and having feeding throats communicating with the lower portions of said chambers, an agitating roller forming a portion of the bottom of each of said chambers at the juncture of the chamber and throat and rotating in contact

with the articles in the chamber, each of said rollers having a notch positioned to catch, carry and release one of said articles at each rotation, and mechanism for rotating said rollers to cause their bottom-forming portions to move in a direction from the chamber toward the throat.

65. In a carton filling and forming machine, the combination with carton filling and forming mechanism, of apparatus for feeding a carton blank having a rear end flap to said filling and forming mechanism, mechanism for applying an adhesive to portions of said rear end flap positioned in the path of movement of the carton blank to said filling and forming mechanism and devices contacting with the non-adhesive bearing portions of said rear end flap to maintain the adhesive bearing portions of the flap out of contact with other portions of the machine.

66. In a carton filling and forming machine, the combination with carton filling and forming mechanism, of apparatus for feeding a carton blank having a rear end flap to said filling and forming mechanism, mechanism for applying an adhesive to portions of said rear end flap positioned in the path of movement of the carton blank to said filling and forming mechanism, and devices contacting with the non-adhesive bearing portions of said rear end flap to maintain the adhesive bearing portions of the flap out of contact with other portions of the machine, comprising projections interposed in the path of travel of the non-adhesive bearing portions of said rear end flap.

67. In a carton filling and forming machine, the combination with carton filling and forming mechanism, of apparatus for feeding a carton blank having a rear end flap to said filling and forming mechanism, mechanism for applying an adhesive to portions of said rear end flap positioned in the path of movement of the carton blank to said filling and forming mechanism, and devices contacting with the non-adhesive bearing portions of said rear end flap to maintain the adhesive bearing portions of the flap out of contact with other portions of the machine, comprising projections interposed in the path of travel of the non-adhesive bearing portions of said rear end flap during a portion of its passage through the filling and forming mechanism.

68. Mechanism for folding the side flaps of carton blanks, comprising means having a plane surface for the support of a blank, a forming plate having straight forming edges registering with the inner edges of the side flaps, and movable fingers adapted to contact with the side flaps and fold them about the edges of the forming plate.

69. The combination of positioning mech-

anism for a blank, an adhesive bearing element spaced from one side of the blank, a movable striker adjacent the opposite side of the blank, and extending across the entire path of movement thereof and means for moving the striker toward and away from the adhesive bearing element after the greater part of said blank has been moved past said element to force the lowermost strip of said blank into contact with said element.

70. The combination of positioning mechanism for a blank engaging a portion thereof only, an adhesive bearing element spaced from one side of the free portion of the blank, and a striker opposite the element and extending across the entire path of movement of the blank and spaced from the reverse side thereof and movable toward and away from the element, to engage the rear portion of the blank to force it into contact with said element.

71. The combination of a supporting plate for receiving a dissociated set of articles, mechanism for moving the articles along the plate in a given direction, and devices for closely associating them as they are moved, and stationary means for limiting said movement.

72. The combination of a supporting plate for receiving a dissociated set of articles, mechanism for moving the articles along the plate in a given direction, and article guides upon the plate converging in the direction of movement of the set, and a stationary element for limiting the movement thereof.

73. The combination of a supporting plate for receiving a dissociated set of articles, article guides at the sides of the supporting plate, spaced therefrom a distance less than the thickness of one of the articles of the set and converging, and a push plate movable to drive the set along the supporting plate between and in the direction of convergence of the article guides, the thickness of said push plate permitting its movement between the supporting plate and the article guides.

74. Mechanism for folding a carton blank into a bottom, a side, and a top, comprising apparatus for holding the blank by its bottom portion and moving it in two directions approximately at right angles to each other, and a bar lying in the path of travel of the side portion of the blank during the first movement of the holding apparatus and shiftable into the path of travel of the top portion during the second movement of the holding apparatus.

75. Mechanism for folding a carton blank into a bottom, a side, and a top, comprising apparatus for holding the blank by its bottom portion and moving it in two directions approximately at right angles to each other, and a bar lying in the path of travel of the

side portion of the blank during the first movement of the holding apparatus and shiftable into the path of travel of the top portion during the second movement of the holding apparatus, the second movement of the holding apparatus being toward the shiftable bar.

76. The combination of a magazine containing chambers for articles and having feeding throats communicating with the lower portions of said chambers, and an agitating roller forming a portion of the bottom of each of said chambers at the juncture of the chamber and throat and rotating in contact with the articles in the chamber.

77. The combination of a magazine containing chambers for articles and having feeding throats communicating with the lower portions of said chambers, an agitating roller forming a portion of the bottom of each of said chambers at the juncture of the chamber and throat and rotating in contact with the articles in the chamber, and mechanism for rotating said rollers to cause their bottom-forming portions to move in a direction from the chamber toward the throat.

78. In a carton filling and forming machine, the combination with carton filling and forming mechanism, of a source of supply for said filling mechanism comprising a magazine containing chambers for articles to be packed and having feeding throats communicating with the lower portions of said chambers, and an agitating roller forming a portion of the bottom of each of said chambers at the juncture of the chamber and throat and rotating in contact with the articles in the chamber, each of said rollers having a notch positioned to catch, carry and release one of said articles at each rotation.

79. The combination of a container for carton blanks, a magazine for articles to be packed, apparatus for selecting a single blank from the container, apparatus for selecting an article from the magazine, apparatus for applying an adhesive to the selected blank, a positioning device for the support of the blank, means for placing the selected article upon the supported blank after said adhesive has been applied, and mechanism for forming the blank into a carton about the article.

80. In a carton filling and forming mechanism the combination of supporting arms, mechanism for positioning a carton blank thereon, and means for supplying the blank with articles to be packed comprising a series of magazines for holding a quantity of the articles, a supporting member upon which the articles to be packed are dropped from the magazine, said member terminating forwardly adjacent the carton blank,

and a push plate movable against the rear end of the articles to position them upon the blank.

81. In a carton filling and forming machine the combination of supporting arms, mechanism for positioning a carton blank thereon, and means for supplying the blank with material to be packed comprising a magazine for holding a quantity of the material, a supporting member upon which the material to be packed is dropped from the magazine, said member terminating forwardly adjacent the carton blank, a push plate movable against the material to position it upon the blank, and a stationary plate for limiting the movement of said material.

82. In a carton filling and forming machine the combination of an oscillating carton table, means for positioning a partially formed carton blank bearing material to be packed thereupon when the table is at one end of its path of oscillation, a carton magazine having its receiving end positioned at the other end of the path of oscillation of the carton table, means coöperating with the carton table to retain the partially formed blank and material thereon during the oscillation of the table, mechanism for oscillating the table, and apparatus for removing the partially formed blank from the table, completing the forming thereof, and positioning the carton formed within the carton magazine comprising fingers before which the partially formed blank is positioned during the oscillation of the table, said fingers being movable to contact with the bottom of the blank and push it into the carton magazine, and an obstruction at the receiving end of the magazine lying in the path of movement of the unformed portion of the blank during its passage from the table into the magazine.

83. In a carton filling and forming machine, the combination of mechanism for applying an adhesive to the rear end flap of a carton blank, apparatus for positioning material to be packed upon the blank, means for completing the forming of the blank into a carton about the material with the exception of said rear end flap, a carton magazine, apparatus for forcing the partially formed blank into the receiving end of the magazine, and an obstruction at the receiving end of the magazine lying in the path of movement of said rear end flap during the passage of the blank into the magazine.

84. In a carton filling and forming machine the combination of mechanism for applying an adhesive to the rear end flap of a carton blank, apparatus for positioning material to be packed upon the blank, means for completing the forming of the blank into a carton about the material with the exception of said rear end flap, a carton maga-

zine, apparatus for forcing the partially formed blank into the receiving end of the magazine, and a member interposed in the path of movement of said rear end flap and 5 adapted to fold the flap upon the body of the partially formed blank and retain it in folded position during the passage of the blank into the magazine.

85. Mechanism for folding the side flaps 10 of moving carton blanks comprising means for support of a moving blank, a forming plate adjacent the supporting means having forming edges registering with the inner edges of the side flaps of the moving blank

and fingers movable into contact with the 15 side flaps, about points adjacent said forming edges as centers of rotation during the travel of the blank past the plate.

In testimony whereof we have signed our names to this specification, in the presence 20 of two subscribing witnesses, on this 1st day of May A. D. 1914.
